UNITED STATES PATENT OFFICE.

CONRAD BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA.

CARD HOLDER.

Application filed December 17, 1924. Serial No. 756,600.

This invention relates to cabinet construction, and more particularly to metal cabinets of the type employed in offices for filing purposes.

5 The object of the invention is to provide novel and advantageous means for supporting an index card on the front of the various drawers of the cabinet or in other positions on the cabinet which may be deemed favorable.

10 More specifically, the invention contemplates simplified means for retaining in a suitable position on the cabinet, and preferably on the front of the drawers, an open frame for support of an index card.

In the attached drawings:

15 Figure 1 shows a fragmentary perspective of the front of a drawer of a cabinet adapted for reception of a card supporting frame made in accordance with my invention;

Fig. 2 is a perspective showing the frame in a detached position;

20 Fig. 3 is a view in perspective showing the rear retaining plate, the plate also being shown in a detached position;

Fig. 4 is a view in perspective of the card frame showing the rear face thereof, and

25 Fig. 5 is a section on the line 5—5, Fig. 1, showing the frame in place on the drawer.

30 In practicing my invention, I provide the front of the drawer 1, or other part of the cabinet to which I may desire to attach the index card-supporting frame, with a pair of parallel slots 2, 2. While in the present instance I have shown these slots perpendicular, it will be obvious as the device is understood that these slots may be horizontal or inclined without departure from the essential features of the invention.

40 The frame proper shown in perspective in Figs. 2 and 4 comprises a flat open body 3 having in the present instance rearwardly extending side flanges 4, 4, the back ends of which turn inwardly, as indicated at 5

45 in Figs. 3 and 5, to form sockets or recesses 6 for reception of the offset flanges 7, 7 of a retaining plate 8, shown in Fig. 3. The upper ends of the recesses 6 as shown in Figs. 2 and 4 are closed by flanges 9, 9, at 50 the upper corners of the frame 3, these flanges being only sufficiently long to close the ends of said recesses or slots. A flange 10 also projects rearwardly from the lower edge of the frame and constitutes a support

for a card or other sheet inserted into the frame through the space between the flanges 9 at the top. The flange 10, as shown in Fig. 3, stops short of the inner edges of the side flanges 5, thereby leaving the lower ends of the recesses 6 unobstructed for insertion of the offset flanges 7 of the retaining plate 8.

In assembling the device, the offset flanges 7 are passed through the slots 2, 2, from the inside of the drawer, the amount of offset 65 of the flanges being sufficient to permit them with the plate in position to project beyond the outer face of the drawer 1. The upper ends of the flanges 7 are then entered in the lower open ends of the slots or recesses 70 6 of the frame and the latter is forced downwardly until stopped by the flanges 9 coming in contact with the upper edges of the said flanges 7, the frame thus being securely supported on the front of the drawer. 75 When thus assembled, a slit 11 is left between the flanges 9 at the top of the frame sufficiently wide to permit insertion of a card or sheet bearing the designation or index character that may be desired, and this 80 card is supported in the frame by the flange 10.

It will be noted that the device eliminates necessity for welding or riveting the frame to the front of the drawer, and provides for 85 its ready detachment. The construction also affords considerable manufacturing advantages both in formation of the parts, which may be stamped from sheet metal, and in the simplicity of assembling. 90

Obviously, the slots 2 may be placed in horizontal positions and the frame inserted from the side of the drawer without departure from the invention, although the form shown is desirable by reason of the relative 95 improbability of accidental dislodgement of the frame.

I claim:

1. The combination with a panel having a pair of parallel spaced slots, a plate having offset flanges adapted for insertion through the slots from one side of the panel, and a card-holding frame having recesses adapted for interlocking reception of said flanges whereby the frame is supported on 100 the other face of said panel.

2. The combination with a panel having a pair of parallel spaced slots, of a retain-

ing element having offset flanges adapted to project through the slots from one side of the panel, a card-holding frame having a recess for interlocking slidable engagement of the flanges, and an element on said frame closing the top of said recess whereby the frame is positively supported by the flanges at the front of said panel.

3. The combination with a panel provided 10 with a pair of parallel slots, of a retaining element having offset flanges adapted to project through the slots in said panel, and a card-holding frame having a recess open at its lower end and closed at the top whereby the frame may be interlocked with said

flanges and supported thereby at the front of the panel.

4. The combination with a panel having parallel spaced slots, of a plate adapted to lie against one face of said panel and having offset flanges adapted to project through the slots beyond the other face of said panel, a card-holding frame having recesses for the reception of said flanges, said recesses being closed at one end and open at the 20 other end so that the frame may be slid over said flanges and be retained thereby in a position on the said other face of the panel.

CONRAD BERGMANN.
